CUT, A CORPORATION OF CONNECTICUT.

ELECTRICAL CONNECTING MEMBER.

1,217,831.

Specification of Letters Patent. Patented Feb. 27, 1917.

Original application filed August 30, 1912, Serial No. 717,842. Divided and this application filed March 13, 1915. Serial No. 14,239.

To all whom it may concern:

Be it known that I, JOSEPH SACHS, a citizen of the United States, residing at Hartford, in the county of Hartford and State of Connecticut, have invented certain new and useful Improvements in Electrical Connecting Members, of which the following is a specification.

This invention relates to electrical connecting members, the primary object of the invention being to provide an article of this character by which access can be readily and easily had to a connector without separating or disassociating the parts when in assembled relation. The device possesses other features of novelty and advantage which with the foregoing will be stated at length in the following description wherein I will set forth in detail that one of the several forms of embodiment of the invention which I have selected for illustration in the drawings accompanying and forming part of the present specification. In this particular form of the invention the device presents a plug such as is insertible into and removable from a socket.

Referring to said drawings:

Figure 1 is an elevation, and,

Fig. 2 is a longitudinal sectional view of a connecting plug involving my invention.

Like characters refer to like parts in both views.

An electrical connecting member involving my invention comprises an insulating portion or body and a contact shell, one of which surrounds the other and a connector interposed between the two parts, one of them having an opening to provide access to the connector. In the present case said insulating portion or body constitutes the core of a plug, the contact shell surrounding the core and the shell having a lateral opening by which the connecting portion of the connector may be reached to connect a wire to or disconnect it from said connector which preferably is electrically connected with the shell. Said connector may be mechanically connected with the shell, thus simplifying the construction. This shell constitutes the lateral or side contact of the plug, the latter being equipped with a central end contact, wires being electrically connected respec-

tively with the end contact generally centrally disposed and the shell.

The numeral 2 denotes a core, constituting a suitable body, and made of some insulating material such as porcelain. The core 2 is surrounded between its ends by the metal contact shell 3 which is externally threaded for practically its entire length to fit the threads of a socket. (Not shown.) Surrounding the contact shell 3 is the ring 4 of suitable insulating material and which is provided with an inset portion 5 snugly fitting an annular external groove in the upper end of the contact shell 3. The ring 4 and shell 3 are, therefore, mechanically connected; they have, however, no positive connection with the core 2. The latter, however, is furnished with a circular circumferential bead 6 to act as a suitable bearing normally for the ring and the shell. The lower portion of the core 2 is shown enlarged at 7, said enlarged portion having a cone surface 8 utilized in the construction shown for expanding the shell 3 into firm contact with the shell of the socket with which the plug is intended to coöperate. As will be inferred, the shell 3 is resilient circumferentially, and this condition can be secured readily by longitudinally slitting the shell as at 9 and 10, the two pairs of slits being diametrically opposite to produce the resilient practically duplicate tongues 11. The lower end of the shell 3 is provided with an inturned conical portion 12 coöoperative with the cone surface 8. When the core 2 bottoms in a socket, its movement will be arrested, although beyond this point the shell 3 and ring 4 can advance independently of the core. On this relative movement the cone portion or inturned lip 12 will ride against the cone surface 8, thereby expanding the shell 3 to obtain a substantial contact with the threaded or equivalent portion of the shell of a socket.

The forward or lower end of the core 2 has a socket or recess 13 intersecting which is the bore or passage 14, the upper end of which opens into the top of the core 2. This bore or passage is of three diameters, the wires of an extension cable being introduced into the largest portion of the bore and being disposed of as will hereinafter more particularly appear. Fitted into the

portion of least diameter of the bore or passage 14, which as shown is located practically at the bottom or base of the plug 2 is the gromet 15, the upper head of which overlies the shoulder formed at the junction of the smallest and intermediate portions of the bore or passage 14. The lower head of the gromet fits against the top of the recess or aperture 13. Threaded into the gromet 15 is a screw 16, the shank of which extends through a perforation or hole in the cup-like approximately conical disk or washer 17 set into the recess or aperture 13, which it will be noted opens into the longitudinally extending hole 18 in the core 2. The upper end of this hole 18 opens into the bore 14. One of the wires of the cable after it leaves the largest portion of the bore 14 is passed through the hole 18 and wound around the shank of the screw 16, the head of said screw when the latter is set causing the cup-like disk 17 to clamp the wire firmly and substantially against the lower head of the gromet or internally threaded rivet 15. This disk or washer 17 acts as a suitable central end contact. Inclosed by the shell 3 is a wire connector 19, the butt of which is suitably fastened as by one or more rivets 20 to said shell interiorly and at the plain or unthreaded portion thereof. The body of the wire connector 19 which can be made suitably by stamping from sheet metal is bowed inwardly, the inwardly bowed portion being somewhat enlarged as at 21 and having an approximately central threaded perforation to receive the shank of the screw 22. The notch 9 substantially centrally between its ends is intersected by the opening 23 shown as circular and which is opposite the head of the screw 22 so that the connecting portion of the connector 19 or that part thereof which carries the screw 22 can be readily reached exteriorly of the shell by way of the opening 23 which is made sufficiently large for this purpose. I have described how one wire of the extension cable is connected with the central end contact of the plug. The other wire of the cable is wrapped one or more times around the shank of the screw 22 between the head of the latter and the enlargement 21 after which the screw is set so that the head can clamp said wires firmly against the enlargement 21. It will be noticed that the connector 19 is disposed in an external groove or recess 24 extending longitudinally of the core 2, the upper end of the groove or recess being in communication with the enlarged portion of the bore 14 to provide for the connection of one of the wires with the connector 19. After the wire in question has been introduced into the groove 24, it may be connected with the connector outside of the shell 3 owing to the presence of the lateral opening or slot 23 in said shell.

The connector 19 in addition to acting as such also serves as a key, the groove or recess 24 constituting a convenient keyway for the connector or key 19, by reason of which relative rotation of the shell 3 and the core 2 is prevented.

It will be noted from the foregoing description taken in connection with the annexed drawings that I provide an insulating body and a contact shell. The insulating body is provided with means for varying the cross sectional extent of the shell, this occurring in the present case on relative movement of the insulating body and the shell. As illustrated the insulating body is in the form of a core, the shell surrounding the same and being expansible by means such as a cone on the core. The present application is a division of my application filed August 30, 1912, Serial No. 717,942. 56

What I claim is:

1. An electrical connecting member comprising an insulating core, a contact shell surrounding the core, a connector inclosed by the shell, said connector being mechanically connected to one of said first mentioned parts, the other part having a recess to receive the connector to key together the core and the shell, the connector being also electrically connected with the shell. 56

2. An electrical connecting member comprising an insulating core, a contact shell surrounding the core, a connector mechanically and electrically connected with the shell, the core having a keyway to receive the connector to thereby prevent relative rotation of the core and the shell. 107

3. An electrical connecting member comprising an insulating body and a contact shell, one of which surrounds the other, and a connector interposed between the two parts, one of said parts having an opening to provide access to the connector, the contact shell being resilient and the insulating body being provided with means for varying the cross sectional extent of the contact shell. 116

4. An electrical connecting member comprising an insulating core, an expansible contact shell surrounding the core, and a connector inclosed by the shell, said shell having a lateral opening to provide access to the connector and the core being provided with means for expanding the shell. 116

5. An electrical connecting member comprising an insulating core, a threaded contact shell surrounding the core, the core being provided with means for expanding said shell, and a connector inclosed by the shell and electrically connected therewith, said shell having a lateral opening to provide access to the connector. 126

6. An electrical connecting member comprising an insulating core, a contact shell surrounding the core, a connector inclosed 126

by the shell, said connector being mechanically and electrically connected with the shell, the latter having an opening to provide access to the connector.

- 5 7. An electrical connecting member comprising an insulating core, a contact shell surrounding the core, a connector inclosed by the shell, said connector being mechanically and electrically connected with the shell, the latter having an opening to pro-

vide access to the connector, the core being recessed to receive the connector to key together the core and the shell.

In testimony whereof I affix my signature in presence of two witnesses.

JOSEPH SACHS.
